REFLECTOR ASSEMBLY FOR A HEAT LAMP

Filed Sept. 13, 1947

FIG. 1.

FIG. 2.

INVENTOR;
JACOB A. MEHR,
By *Jacoba A. Mehr*
ATTORNEY.

UNITED STATES PATENT OFFICE

152,113

DESIGN FOR A REFLECTOR ASSEMBLY FOR A HEAT LAMP

Jacob A. Mehr, St. Louis, Mo.

Application September 13, 1947, Serial No. 141,381

Term of patent 7 years

(Cl. D48—20)

To all whom it may concern:

Be it known that I, Jacob A. Mehr, a citizen of the United States, residing at St. Louis and State of Missouri, have invented a new, original, and ornamental Design for a Reflector Assembly for a Heat Lamp, of which the following is a specification, reference being had to the accompanying drawing, forming a part thereof.

In the drawing:

Fig. 1 is a plan view of a reflector assembly for a heat lamp, showing my new design, and

Fig. 2 is a side elevational view thereof.

I claim:

The ornamental design for a reflector assembly for a heat lamp, as shown.

JACOB A. MEHR.
